UNITED STATES PATENT OFFICE

KELLEY D. EVANS, OF HAMILTON, OHIO, ASSIGNOR OF ONE-HALF TO C. E. HOOVEN, OF HAMILTON, OHIO

AUTOMATIC TYPEWRITER

Application filed June 12, 1926. Serial No. 115,659.

This invention relates to automatic typewriters and particularly to that type of automatic typewriters controlled by a record sheet or strip having perforations which 5 select the keys to be actuated and permit suitable parts or members connected with the key levers of the keyboard to be moved into the path of a motor driven actuator which depresses the keys and actuates the 10 type bars.

The present invention embodies numerous improvements in the general type of machines specified above, one of the objects of the invention being to avoid the actuation 15 of the keys during the normal operation of the machine when controlled by the perforated record sheet.

A further object is to provide efficient and practical means whereby the motor driven 20 actuator causes the operation of the type bars whether the selection occurs through the perforated record sheet or by the manual depression of the keys corresponding to such type bars. In other words it is one of the 25 objects to provide a typewriter of the automatic type wherein the type bars are brought into operative relationship with the actuator whether through the medium of the record sheet or through the actuation of the 30 keys, so that in both instances the type bars will be actuated by a motor driven part, and in both instances the printed impressions will be exactly the same in appearance, thus making it possible for the operator to stop 35 the feed of the record sheet at any point and to insert in the communication being written matter not covered by the record sheet without changing to the slightest degree the appearance of the typewritten matter.

40 The above and other objects are attained by my invention which may be here briefly summarized as consisting in certain novel details of construction and combinations and arrangements of parts which will be described in the specification and set forth in the appended claims.

In the accompanying sheets of drawings wherein I have shown an embodiment of my invention which operates very effectively, Fig. 1 is a rear view of my improved

automatic typewriter, this view and at least part of the views to be referred to, either omitting or showing conventionally certain parts unessential to the invention, and which are commonly employed on typewriters; 55 Fig. 2 is a horizontal sectional view substantially along the irregular line 2—2 of Fig. 3; Fig. 3 is a vertical transverse sectional view; Fig. 4 is a similar view but looking in the opposite direction; Fig. 5 60 is a fragmentary sectional view showing some of the parts of Fig. 3 but with an actuating lever associated with the type bar illustrated in Fig. 3 moved to a position where it is about to be rocked or actuated 65 by the motor operated actuator, the selection having been brought about by the perforated record sheet; Fig. 6 is a similar 65 view with a few additional parts shown and with the type bar thrown to printing position, this view showing the relative positions which the parts occupy at the end of the actuating movement through the selection brought about by the perforated record sheet; Fig. 7 is a similar view but omitting 70 part of the elements shown in Fig. 6 showing how the actuating lever may be actuated when the selection is made through the manual depression of the key associated with the type bar instead of through the perforated 75 record sheet; Fig. 8 is an end view of the machine looking toward the right hand end of Fig. 1, parts being shown in section; Fig. 9 is a rear view omitting some of the parts and some being in section and broken 80 away to illustrate the structure at the top of the machine omitted from Fig. 1; Figs. 10 and 11 are respectively, a vertical sectional view and a horizontal sectional view showing certain details for the actuation of 85 the pawl employed in spacing the carriage. 90

Referring now to the drawings, my improved typewriter includes a frame 10 at the front of which is a keyboard corresponding to the keyboard of an ordinary typewriter, 95 a few of the key levers being illustrated at 11. These key levers are pivoted on a cross-rod 12 supported by frame 10 and swing in the slots of a comb 13. Each key lever has a downward extension 14 terminating in a 100

forwardly projecting part 15, the downward extension having connected to it a spring 16 connected to a spring bar 17 extending across the front part of the frame 10, the springs 16, one of which is associated with each key lever, serving to return the key levers to normal position after being depressed.

My improved typewriter has the usual type bars 18, only one of which is illustrated, these type bars being pivoted as usual on a fulcrum wire 19 (Fig. 10) mounted in the customary slotted segment 20, and when the type bar is swung to printing position it enters the usual guide indicated at 21. I have indicated the platen conventionally at 22, but have not illustrated the carriage which supports the platen as this may be of suitable or usual form. However, portions of the carriage frame are illustrated at 22^a and this frame will be referred to later.

It will be observed that there is no direct connection between the key levers and the type bars. On the other hand each type bar 25 is connected by a pin and slot connection with a sub-link 23, the sub-links for all the different type bars being fulcrumed on a wire or rod 24 (Fig. 3) extending transversely across the machine in a slot of a forwardly facing comb 25. Each sub-link has a forwardly and upwardly inclined slotted portion 26 engaged by a pin 27 of an actuating member 28, heretofore termed the actuating lever, one of which is provided for each of the different key levers of the keyboard.

The different actuating levers 28 are arranged side by side and are spaced apart by the teeth of front and rear combs 29 and 30 (Fig. 3), and all of these actuating levers are independently capable of a slight sliding movement to bring them into the path of the motor driven actuator (53 to be described later), and of a rocking movement 45 to shift the sub-links 23 which in turn actuate the type bars 18 as explained above.

The rocking movement of the actuating levers 28 occurs about a stationary fulcrum shaft or bar 31, which extends across the frame of the machine and which engages in slots 32 on the lower sides of the actuating levers. The latter are supported by the fulcrum shaft 31 and by a cross-bar 33 forming a part of comb 30, and they are normally held in the position illustrated in Fig. 3, at which time the rear portions of the actuating levers rest on the cross-bar 33, by springs 34 connected to the upper rear portions of the actuating levers and to a rear spring bar 35.

At the upper forward part of each actuating lever is an extension 36 which, when the actuating lever is in the position illustrated in Fig. 3, is normally out of the path of the motor driven actuator, but which when the actuating lever is slid forwardly

either through the selection by the record sheet or by depression of the corresponding key lever, comes into the path of the actuator and is rocked to the position shown in Fig. 6 so as to swing the corresponding type bar to printing position. Additionally, the actuating lever is provided at its rear end with a spring actuated pin 37, which as will be explained, is normally held in upper or retracted position by the unperforated part of the record sheet but is permitted to be lowered by a pin spring 38 (Fig. 4) when a perforation of the record sheet comes under the pin. Similarly the front end of the actuating lever has a spring actuated pin 39 which is normally held retracted by the forward extension 15 of the corresponding key lever 11, but this pin is adapted to be moved upwardly under the action of the pin spring 40 (Fig. 6) when the key lever is depressed bringing a slot 41 opposite the pin 39 (Fig. 7).

The perforated record sheet which I propose to employ in my improved machine may be exactly similar to those which have been used for a great many years on the so-called Hooven Automatic Typewriters, a record sheet of this general type being illustrated conventionally in Pillings Patent No. 1,175,986 and it may be formed or produced by a perforating machine such as illustrated in the Pillings patent above mentioned or in the McCall Patents No. 1,048,560 and No. 1,083,290. This perforated sheet is generally endless and is provided along its margins with perforations adapted to be engaged by the teeth of the feeding sprockets, and between the sprocket perforations the sheet is provided with actuating perforations which in this instance when they come beneath the spring pins 37 permit the latter to drop into them so that the actuating levers 28 will be shifted in the manner hereinafter more fully explained.

In Figs. 3 and 4 of the drawings the record sheet is indicated at 42, this sheet being adapted to travel over a shield 43 which extends across the lower rear part of the machine, as illustrated in the drawings. This shield is preferably formed of two pieces of properly shaped sheet metal and its upper part is cylindrical, there being between the pieces forming the shield a slot 44 which extends the full length of the shield and is directly beneath the rear pins 37 of the actuating levers 28.

Supported within the shield is an oscillating bar 45 which extends the full length of the slot 44 and has its outer portion curved to conform to the cylindrical curvature of the upper part of the shield and is adapted to move back and forth in the slot 44, so that when the rear spring pin 37 of any actuating lever 28 is lowered into the path of this

oscillating bar, the corresponding actuating lever will be moved forwardly.

The bar 45 is supported on a shaft 46 extending centrally through the upper part of the shield and supported in the side members 5 of the frame 10. Fixed to this shaft are sprocket wheels 47 which feed the perforated record sheet 42, one of the sprocket wheels being provided with a ratchet wheel 48 adapted to be operated by a pawl 49 (Fig. 3) hereinafter described so that the record sheet will be given a step-by-step movement.

It might be here stated that one end of shaft 46 is journalled in one of the side members of frame 10, as indicated in Fig. 2, but the other end is journalled in an upstanding supporting arm 46^a which is in the plane of the opposite side of frame 10, this arm being at the free end of a horizontal arm 46^b 20 extending across beneath shaft 46 from the first mentioned side of frame 10, as indicated in Fig. 4. The free end of arm 46^b and of the upright supporting arm 46^a lie in a slot or opening 46^c extending up from the 25 bottom of the adjacent side of frame 10, as indicated in Figs. 2, 4 and 8. This forms virtually an open-ended support for shaft 46 and its associated parts, making it possible to slip an endless record sheet inwardly from 30 the side having opening 46^c over sprockets 47 and shield 43.

The rear oscillating bar 45 which is adapted to engage the rear spring pins 37 is one of two simultaneously moving oscillating bars, the other being illustrated at 50, this oscillating bar being adapted to engage the front spring pins 39 of the actuating levers 28 when the latter are moved upwardly through the slots 41 of the key lever 40 extensions 15 when the key levers are depressed so that this front oscillating bar may move the actuating levers forwardly by engaging the front spring pins 39 in the same manner that the rear oscillating bar 45 may 45 move the actuating levers by engaging the rear spring pins 37. This bar 50 is supported by arms 51 secured to a rock shaft 52 which extends across the lower front portion of the machine and is journalled in the 50 sides of the frame 10.

It was heretofore explained that when an actuating lever 28 is moved forwardly the front upward extension 36 is moved into the path of a motor driven actuator so as to 55 rock the actuating levers about the fulcrum shaft 31 and thus swing the type bars to printing position, it being understood that when the actuating levers 28 are in their normal rear positions they are not engaged 60 by the actuator. This actuator is in the form of a bar 53 which extends across the upper front part of the machine and is supported by two arms 54 secured to a rock shaft 55 which extends across the machine and is 65 journalled in the sides of the frame 10.

The bars 45 and 50 which move the actuating levers 28 forwardly have substantially a horizontal oscillatory motion, while the motor driven actuator 53 which rocks the actuating levers 28 has a substantially vertical oscillatory motion.

The main drive shaft of the machine is shown at 56. This shaft is rotated by a motor which may be located at any suitable point but in this instance is shown conventionally at 57, and as illustrated is supported inside the frame 10 and has a shaft 58 connected to the shaft 56 by spiral gears 59 or other suitable form of speed reducing gears.

This shaft 56 which rotates continuously as long as the machine is in operation, is provided near one end with two eccentrics 60 and 61 (Figs. 3 and 9) which are secured to the shaft in fixed relation to each other, 85 one being preferably 90° in advance of the other. One of these eccentrics actuates the two horizontally oscillating bars 45 and 50 as well as the sprockets which feed the record sheet, and to this end it is engaged 90 by an eccentric sleeve having a rearwardly projecting arm 62 connected to an arm 63 secured to the boss of one of the arms which support the oscillating bar 45 from shaft 46 (Figs. 3 and 6). It also has a relatively 95 short forwardly projecting arm 64 pivotally connected to a link 65, which in turn is pivoted to an arm 66 secured to the front rock shaft 52, which actuates the front oscillating bar 50.

The arm 62 carries the pawl 49 which engages one of the sprockets 48 which are secured to a shaft 46 and which actuate the record sheet. During normal operation on each rear stroke of arm 62 the two oscillating bars 45 and 50 swing forwardly and coincidentally the record sheet is moved forwardly one step. However, it is generally the case that when the typewriting is done through the actuation of the key levers 11, 110 it is desired that the record sheet be stationary and accordingly provision is made for rendering inoperative the pawl and ratchet mechanism which feeds the record sheet. This is accomplished in this instance, 115 by a short bell-crank lever 67 (Fig. 3) which when rocked from normal position is adapted to move the pawl 49 downwardly so as to be clear of the teeth of ratchet 48. This bell-crank lever may be operated in 120 any suitable manner as by a rod 68 which may extend forwardly to the front of the machine where it may be shifted by a key or other means within the convenient reach of the operator. It will be understood, of course, that by disengaging the pawl 49 from the ratchet 48 while the feed of the record sheet is stopped, the remaining parts of the machine continue to operate, this being essential because of the fact that with 125

my improved construction the type bars are not actuated directly by the key levers.

The other eccentric provided on shaft 56 is engaged by an eccentric sleeve provided with an upwardly extending arm 69 (Figs. 3, 5 and 6) which at its upper end is connected to one of the arms 54 supporting the actuator 53 from rock shaft 55. By reason of the arrangement of the eccentrics 60 and 61 as described, the actuator 53 is swung downwardly immediately after the bars 45 and 50 are swung forwardly so that in the event a perforation of the record sheet has permitted the rear spring pin 37 of any particular actuating lever 28 to move downwardly into the path of the oscillating bar 45, or in the event a key lever 11 has been depressed so as to permit the front spring pin 39 of the corresponding actuating lever 28 to spring upwardly in front of the front oscillating bar 50, the actuating lever is first moved forwardly from the position shown in Figs. 3 and 4 to the position shown in Fig. 5, so that the upward extension 36 of the actuating lever is in the path of the actuator 53, and then the actuator engages said extension of the actuating lever swinging the latter to the position shown in Fig. 6, causing the type bar to be swung to printing position, or from the position shown in Fig. 5 to the position shown in Fig. 6.

As soon as the actuating lever is rocked to the position stated above causing the printing impression to be made, the spring pin 37 or the spring pin 39 as the case may be, is released from the corresponding oscillating bar 45 or 50, whereupon the actuating lever 28 is restored to its former position and the extension 36 thereof slides back from beneath the engaging lower surface of the actuator 53 by the action of spring 34, the type bar coincidently dropping back onto its support. The return of these parts to their normal positions takes place quickly enough to permit the quick duplication of the operation even with the same actuating lever and type bar.

It might be here mentioned that the rock shaft 55, to which the actuator 53 is attached, is instrumental in the performance of another function, i. e. the step-by-step feeding or spacing of the carriage following each printing impression, and in this connection it will be recalled that in the early part of the specification it was stated that the feed of the carriage and the movements thereof for tabulations or indentations and for its return, are done positively through motor actuated means, and this mechanism will now be described.

The carriage frame 22^a, portions of which only are shown, (the carriage itself being omitted as it forms no part of the present invention) is slidably mounted on two way-

rods 70 and 71. Though the particular gear members herein illustrated for imparting the back and forth movements to the carriage frame are not essential to my invention, in this instance the carriage frame is provided on its lower rear side with a fixed shaft 73 having a spiral thread or groove extending substantially throughout its length. This spirally grooved shaft is engaged by the equivalent of a nut designated as a whole in Fig. 1 by the reference character 74, this nut being a rotatable member held from endwise movement and provided with a pin which extends inwardly into the spiral groove. This nut consists of a sleeve having at one end a gear 75 and at its other end a ratchet wheel 76. This ratchet wheel is adapted to be engaged by a pawl 76^a (Fig. 3) pivotally mounted at the upper end of an arm 77 secured to rock shaft 55 which, as previously explained, is rocked back and forth with the oscillations imparted to the motor driven actuator 53. The pawl is pressed upward by a spring 76^b shown in Fig. 4. The manner in which this pawl is controlled so that it causes the carriage to feed one step immediately after a printing impression is made will be explained hereinafter.

The gear 75 is engaged by a gear 78 carried by a sleeve 79 pinned, or otherwise secured to a shaft 80 which is motor driven in a manner to be explained presently. The sleeve is preferably provided with a fairly deep groove 81 (Fig. 1) to permit the actuation of and to guide the pawl 76^a. This shaft 80 has its outer end mounted in a suitable bearing in one side of frame 10 and its inner end is journaled in a frame 82, the base of which extends down to and is suitably secured to the cross bar forming a part of comb 25. At its upper end this frame 82 has a pair of spaced arms 82^a located on opposite sides of the nut 74 and of the gear 78 with its sleeve 79 and forming the inner bearings for shaft 80 and also serving to hold the nut 74 against endwise movement on the spirally grooved shaft 73 of the carriage. It will be observed from Figs. 1 and 3 that the lower portion of the frame 82 is curved over rock shaft 55 and that the arm 77 which actuates the pawl 76^a extends through a slot in this frame.

The shaft 80 near its outer end is connected by bevel gearing 83 to a diagonally disposed shaft 84 provided at its lower end with a bevel gear 85 adapted to be engaged by either of two bevel gears 86 and 87 splined to the main driving shaft 56 and through the medium of which shafts 84 and 80 may be rotated in either direction so as to rotate the nut 74 in either direction and move the carriage frame 70 either to the right or left.

Suitably connected to a bracket 88 on the base of the machine (Fig. 9) are two gear shifters 89 and 90 which are adapted to

move the gears 86 and 87 into and out of engagement with the bevel gear 85. These gear shifters are adapted to be actuated by two actuating levers 28^a and 28^b which are similar to the actuating levers 28 associated with the printing key levers, and are mounted and have movements or are actuated in precisely the same way as the actuating levers associated with the printing key levers, being selectively controlled either by the perforated record sheet or by the depressing of two shift keys carried by the key levers forming a part of the regular keyboard equipment. These two actuating levers 28^a and 28^b differ from the main actuating levers 28 in the respect that their forward ends are connected by links 91 (Figs. 1 and 9) to the two shifters 89 and 90, the arrangement being such that when either actuating lever 28^a or 28^b is rocked, the corresponding bevel gear 86 or 87 is moved into engagement with the bevel gear 85. The gear 87 is utilized for the carriage return and the gear 86 for moving the carriage for indenting or tabulating purposes. When the gear 87 is shifted by the actuating lever 28^b into engagement with the gear 85 in order to return the carriage, it is held in driving engagement with gear 85 until the carriage is given its full return movement. This is accomplished in this instance by providing on the end of the sleeve forming a part of gear 87 a disk 92 (Fig. 9) having its periphery beveled in opposite directions and engaged by a so-called spring point 93 which by engaging one beveled side or the other of disk 92 holds the gear 87 in either engaged or disengaged position. The gear 87 is automatically disengaged when the carriage is returned to the desired position by a releasing lever 94 which extends up alongside of the frame and has its lower end forked and in engagement with the sleeve carrying gear 87 while its upper end is behind the head 95 on the end of rod 71 which is one of the two rods on which the carriage frame is supported, and which corresponds to the so-called typewriter front rod of ordinary typewriters, this rod carrying an adjustable stop 97 which can be positioned by the usual means wherever desired and is adapted to be engaged by a shoulder 98 (Figs. 4 and 8) carried by the carriage frame. The rod 71, unlike the corresponding rod in the usual typewriter construction, is capable of a slight endwise movement, being normally held in one extreme position by a spring 99 (Figs. 1 and 9) engaging the head 95. When the shoulder 98 of the carriage engages the adjustable stop 97, the rod 71 is shifted endwise (against spring 99) sufficiently to rock lever 94 far enough to cause the disk 92 to pass the spring point, in which event the gear

86 is disengaged from the gear 85 and is held in disengaged position.

The gear 86 used for tabulating or indenting purposes is held in engagement with gear 85 until automatically released by the following means: The rear end of the actuating lever 28^a which as before explained shifts the gear 86 into engagement with gear 85, is provided with an upstanding rod 100 (Figs. 8 and 9) connected to a pin 101 (Fig. 9) of the tabulating frame 102 which is adapted to rock back and forth on the main frame 10 of the machine, but unlike the tabulating frame of ordinary typewriters, is capable of slight endwise movement on the main frame. The function of the rod 100 connected to pin 101 of the tabulating frame is to swing it inwardly and when this occurs the frame is held in its inward position by reason of the fact that a pin 103 (Figs. 8 and 9) carried by the tabulating frame is by the inward movement carried slightly above a locking plate 104, and when the pin passes above the locking plate the tabulating frame is moved slightly in endwise direction by a spring 105 (Fig. 9) surrounding one of the pivots for the frame. This carries the pin over the locking plate which is therefore held in its inwardly swung position (to which it was moved by rod 100) until the tabulating movement is completed, and when this occurs the tabulating frame is moved back against the pressure of spring 105 by the engagement of a shoulder 106 with an adjustable stop such as indicated at 107 carried by the tabulating frame (Figs. 8 and 9). The slight blow imparted to the adjustable stop by the shoulder of the carriage frame moves the tabulating frame (against spring 105) sufficiently far that the pin 103 is carried past the locking plate 104, in which event the tabulating frame again swings outward under the action of spring 108 causing gear 86 to be disengaged from gear 85.

Thus it will be seen that a perforation of the record sheet or the manual depression of a carriage shift-key causes the actuator 53 to rock actuating lever 28^a so as to cause gear 86 to be moved into engagement with gear 85, and that it will be held in engagement therewith so as to move the carriage to give the right indentation or tabulation, the amount of which will depend upon the adjustment given to stop 107, the carriage thus being shifted by the motor after which the driving engagement is broken by the automatic disengagement of gear 86 from gear 85.

Likewise it will be seen that either a perforation of the record sheet or the depression of a shift-key causes gear 87 to be shifted into engagement with gear 85 so as to cause the carriage to be returned by the

motor, gear 87 being held in engagement with gear 85 until the carriage is returned to a point determined by the position of the adjustable stop of the front rod 71 of the main frame which then causes the disengagement of gear 87 from gear 85.

It is to be understood that normally gear 85 is disengaged from both gears 86 and 87 and it is only when the tabulating or return movements are being imparted to the carriage frame that either of these gears 86 or 87 is in driving engagement with gear 85.

The fact that gear 85 is normally free of the driving gears 86 and 87 makes it possible for the step-by-step carriage spacing to be accomplished by the power of the motor which is applied as heretofore explained by the rock shaft 55 and pawl 76^a which engages the ratchet wheel 76. Each time the pawl engages the ratchet wheel and moves it forward one step, the nut 74 as a whole is rotated through one step sufficient to space the carriage frame. During this movement of the nut the gears 75, 78, shaft 80, gears 83 and shaft 84 with its gear 85, turn idly.

Inasmuch as the rock shaft 85 is rocked by one of the arms supporting the actuator 53 and by the arm 69 actuated by the eccentric on the main motor driven shaft 56, it is obvious that the pawl 76^a is given one forward stroke during each revolution of shaft 56, this stroke occurring immediately after the type bar has been swung to printing position and during the return or upward stroke of the actuator 53. However, it is desirable, and in fact necessary, both when the selection occurs by the perforated record sheet or by the manual depression 40 of the key levers, that the spacing movements be imparted to the ratchet wheel 76 only after printing impressions are made, regardless of the rate these impressions are made with respect to the rotation of the 45 motor driven shaft 56 except for the spacing between words which is taken care of by a third special actuating lever here designated 28^c which is similar in its mounting and manner of movement to the actuating 50 levers 28 which actuate the type bars and the two previously mentioned special actuating levers 28^a and 28^b.

In order that the step-by-step feeding movements imparted to the ratchet wheel 55 76 may be caused to occur only after each printing operation and for each word spacing, a control mechanism for the pawl 76^a is employed, and in carrying out this part of my invention I utilize the so-called universal bar commonly employed on typewriters, but with new functions to be performed by it. This universal bar includes the arc-shaped piece 109, this member as customary lying in a slot on the rear of the slotted segment 20 in position to be engaged and moved

rearwardly by each type bar 18 as it is swung upwardly to printing position. From this piece extend rearwardly arms 110 (Fig. 11) which are connected to the upstanding arms 111 of a lever 112 (Figs. 1, 70 3 and 6) pivotally supported on the rear part of frame 82, a spring 113 (Fig. 3) being attached to the lever to hold these parts in their forwardmost positions with the arc-shaped member 109 in the slot on the rear 75 side of the slotted segment 20. The arrangement is such that on each actuation of any type bar this universal bar is moved rearwardly as in ordinary well known typewriters.

One of the arms 110 is, in this instance, provided with a laterally extending stud 114 (Fig. 11) which normally lies over a lug 115 on pawl 76^a, the lug being shown in Figs. 6, 10 and 11. As long as the universal bar is 85 in its forward or normal position and the stud overlies the lug on the pawl, the pawl is held out of engagement with the ratchet wheel 76 and therefore regardless of the number of oscillations which this pawl may have 90 by the rocking of shaft 55 the ratchet wheel is not actuated, but when the universal bar moves rearwardly as by the actuation of a type bar the stud rides past the lug 115 on the pawl and this allows the pawl to move 95 upwardly into engagement with the ratchet wheel so that the pawl will on its next rearward stroke turn the ratchet wheel one step. As the universal bar moves back or forwardly toward the front of the machine to 100 its normal position, the stud passes under the lug 115 to a position forwardly of it, but on the return of the pawl the lug, by reason of the fact that it has an inclined top 105 surface, again rides beneath the stud.

For the word spacing, i. e. to space the carriage the usual distance after each word is completed, the special actuating lever 28^c is utilized, which lever is arranged directly beneath a downward and forward extension 116 of lever 112 (Figs. 1 and 3), this actuating lever being adapted to be shifted by the actuator 53 as before through the selection by the perforated record sheet or by the manual depression of a special shift-key 115 or bar as may be found desirable, the key, if the same is utilized, being on a key lever such as those previously described and designated 11 and serving to move this special actuating lever 28^c forwardly so that its front end may 120 be shifted downwardly by the actuator in precisely the same manner as previously described for the other actuating levers. As the rear end of this actuating lever 28^c is elevated it engages the extension 116 of lever 112 and shifts the universal bar so as to release the lug 115 of pawl 76^a from the stud 114 in precisely the same way as the lug is released from the stud by the action of the different type bars.

The various parts and mechanism described above for automatically and positively moving the carriage for word spacing, for tabulating purposes, and for the carriage return, are not claimed herein, but 5 are claimed in a companion application Serial No. 289,131, filed June 21, 1928.

For elevating the platen so that the upper case letters of the type bars will be effective 10 for printing, the shifting mechanism ordinarily employed in typewriters may be utilized except that a fourth special actuating lever similar to those already described will be suitably connected to the lift frame of 15 the typewriter, this lever being shifted by the actuator 53 in the manner previously described and being controlled either through the record sheet or by the usual shift-key which will bring this special actuating lever 20 into the path of movement of the actuator 53. It is not deemed necessary, however, to illustrate this special actuating lever as its operation will be understood by one skilled in the art.

25 The operation is as follows: The perforated record sheet which as already stated is generally endless, is slipped over the sprockets 47 and shield 43 by inserting the sheet over these parts through the slot or 30 opening 46^c in one of the sides of the frame. The motor can then be started by closing a conveniently located switch, or the motor may previously have been in operation and may be caused to operate the machine by 35 throwing in a suitable clutch. The motor now driving shaft 56 swings the motor driven actuator 53 up and down and swings the oscillating members 45 and 50 back and forth, these last two mentioned members 40 swinging in unison, the forward motion being slightly in advance of the downward stroke of the actuator 53. Simultaneously with the forward stroke of the oscillating members 45 and 50 the pawl 49 by its engagement with the ratchet 48, causes the 45 sprockets and, therefore, the record sheet to be moved forwardly one step. The unperforated portion of the record sheet holds the pins 37 at the rear ends of the actuating 50 levers 28 out of the path of movement of the rear oscillating member 45, but when a perforation comes beneath one of these pins the latter drops downwardly in front of the oscillating member causing the actuating 55 lever which carries the pin to be moved forwardly so that the front upward extension thereof comes into the path of the downwardly moving actuator 53 which rocks 60 the actuating lever causing the corresponding type bar to be swung to printing position. In this way the different type bars are operated automatically, it being understood 65 that during this automatic operation the key 70 levers 11 are not moved since they have no

mechanical connection with the actuating levers.

As each type bar swings to printing position the pawl 76^a is permitted to engage the ratchet 76 and as the actuator swings upwardly the pawl moves rearwardly turning the nut 74 one step so as to positively space the carriage one step and thereby position the platen for the next letter, it being understood that the pawl 76^a is prevented from shifting the ratchet and spacing the carriage except after a printing impression is made and except for the word spacing, the pawl in the latter case being released by the movement of the special actuating lever 28^c 80 which brings about the release of the pawl 76^a the same as is done by a type bar. Thus the spacing both for the letters and for the words is done positively through the pawl and ratchet mechanism causing the carriage 85 frame and carriage to be moved laterally step by step.

If at any time it is desired to insert matter not covered by the record sheet such as the name, address, salutation, and the like, 90 or a paragraph or more in the body of the matter being written, the operator disengages the pawl 49 so as to prevent the feed of the record sheet. The matter thus referred to is inserted by the manual operation of the key levers, but as explained in the course of the detailed description, the depression of the key levers does not directly cause the type bars to be swung to printing position but on the other hand they are 100 actuated as before by the motor driven actuator 53, the manual depression of any particular key lever simply permitting the spring pin at the forward end of the corresponding actuating lever to be elevated 105 in front of the forward oscillating bar 50 as indicated in Fig. 7, whereupon the actuating lever is moved forwardly into the path of the actuator 53. That is to say, when the key is depressed, the forward motor actuated oscillating member 50 is rendered effective to shift the actuating lever 28 corresponding to that key into the path of the actuator 53 whereupon the actuating lever is rocked and the corresponding type bar is 110 swung to printing position without any further downward movement on the part of the key or key lever since, as pointed out above, the latter has no mechanical connection with the type bar or with the actuating 115 lever associated therewith.

It will be seen, therefore, that I have provided what may be truly stated to be an automatic typewriter as distinguished from the application of an automatic operating mechanism to a typewriter. Heretofore these have been marketed in the form of two units, one the typewriter and the other the automatic operating mechanism therefor. By my invention, I provide the operating 120 125 130

mechanism and typewriter in a single unit with provision for automatically operating the type bars wholly independent of and without affecting the keyboard, together with means whereby the machine can be manually operated, the effect of the depression of the keys being simply to trip the actuating levers or to shift them to a position to be engaged by the motor driven actuator identically as when the machine is operated automatically. During this manual operation the letter or word spacing is accomplished by positively moving the carriage through the medium of the pawl 76^a in the same manner as when the selection occurs through the perforated record sheet, the operator depressing the spacing key or bar to bring about the word spacing, this causing the special actuating lever 28° to be operated by the actuator.

As explained above, the carriage is moved positively for letter and word spacing by the motor actuated pawl which gives the nut 74, and therefore the carriage frame and carriage, a step-by-step movement. Additionally, as explained above, the indenting or tabulating and return movements are imparted to the carriage frame and carriage, the nut 74 then being rotated continuously (as distinguishing from the step-by-step movement imparted by the pawl) through the motor driven shafts and gears, the engagement of the proper gear 86 or 87 with the gear 85 being caused by the motor driven actuator 53 and controlled either by the perforated record sheet or by the manual depression of the proper key, and the gears being disengaged automatically when the carriage reaches the proper position predetermined in each instance by the position of an adjustable stop.

The carriage can be moved by hand in either direction, if desired, when the pawl 76^a is disengaged from the ratchet 76 (it being normally disengaged as explained above) and to permit this it is only necessary to depress a small lever 117 which as shown in Fig. 1, is supported adjacent the ratchet wheel 76, this lever which is spring pressed holding in position a small detent 118 shown by dotted lines in Fig. 6, and normally engaging the ratchet wheel 76. By depressing this lever as just stated, the detent is released sufficiently from the ratchet wheel 55 to permit the latter to turn freely in either direction, thus permitting the carriage frame and carriage to be moved by hand in either direction.

While I have shown one construction only which practice has demonstrated answers the necessary requirements, it is obvious that the machine may be modified in many of its details and I, therefore, do not desire to be confined to the particular construction shown and described as the principle of the

invention may be carried out in other ways. I aim, therefore, in my claims to cover all modifications which do not involve a departure from the spirit and scope of my invention as set forth in the appended claims.

Having thus described my invention, I claim:

1. An automatic typewriter comprising a unitary machine having a typewriter keyboard, means for accommodating a perforated record sheet, type bars individual to the different keys of said keyboard, an automatically operated constantly moving actuator for said type bars, actuating members connected to the type bars, and motor driven means controlled either through the record sheet or manually by the actuation of said keys for shifting the actuating members into the path of the actuator to cause the actuator to operate the type bars independently of the keys.

2. An automatic typewriter comprising a unitary machine having a typewriter keyboard having keys and key levers, type bars associated with the key levers of said keyboard, means for accommodating a perforated record sheet, an automatically operated continuously moving type bar actuator, means whereby said actuator is caused to shift the type bars to printing position through the manual operation of the corresponding keys of said typewriter keyboard, and separate means whereby the actuator is caused to shift the type bars to printing position through selection by the record sheet independently of the keyboard and without shifting the keys and key levers thereof, said unitary machine having a frame in which all of said parts of the machine are supported with the keyboard at the front of the frame and the means for accommodating the perforated record sheet at the rear of the frame.

3. In an automatic typewriter having a typewriter keyboard, means for accommodating a perforated record sheet, type bars associated with the different keys of said keyboard, an actuating lever connected to each type bar independently of the key and key lever associated therewith, a motor operated actuator, and motor operated means controlled either by the record sheet or by the manual depression of a key corresponding to a type bar for shifting the associated actuating lever into the path of the actuator so that the latter will then rock the actuating lever and cause a movement of the type bar to printing position independently of the keyboard.

4. An automatic typewriter comprising a unitary machine having a typewriter keyboard with key levers, type bars associated with the key levers, means for accommodating a perforated record sheet, actuating members connected to the different type

bars, an automatically operated actuator, and motor operated means controlled through the record sheet or through the manual operation of the keys for shifting the actuating members so that they may be engaged by the actuator thereby creating operative connections with the type bars independently of the key levers.

5. In an automatic typewriter having a typewriter keyboard, type bars associated with the different keys but mechanically independent thereof, provision for accommodating a perforated record sheet, a type bar actuator, actuating members connected with the type bars and adapted to be selectively engaged by the actuator, automatic motor operated means rendered effective by selection either through the record sheet or by the manual depression of the keys for causing the actuator to engage and shift the actuating members, and motor operated means for giving the actuator a constant and regular motion.

6. An automatic typewriter having a typewriter keyboard, type bars individual to the different keys but mechanically disconnected therefrom, provision for receiving a perforated record sheet, actuating members operatively connected to the type bars, an automatic motor operated type bar actuator adapted to engage and shift said members, and automatic motor operated means rendered effective by selection either through the record sheet or by the manual operation of the keys for moving said members to a position to be engaged by the actuator.

7. In an automatic typewriter having a keyboard, type bars and provision for receiving a perforated record sheet, an automatic motor operated type bar actuator, actuating members connected to the type bars and adapted to be selectively engaged by the actuator, two motor operated devices for causing the actuator to engage and shift the actuating members, one of said devices being rendered effective through selection by the record sheet and the other by the manual depression of the keys.

8. In an automatic typewriter having a keyboard, type bars and provision for receiving a perforated record sheet, actuating members connected to the different type bars, an automatic motor operated actuator adapted to engage and shift said actuating members so as to move the type bars to printing position, and two motor operated members one rendered effective by the record sheet and the other by the manual depression of the keys for shifting said actuating members to a position to be engaged by the actuator.

9. An automatic typewriter having a typewriter keyboard, type bars individual to the different keys but mechanically disconnected therefrom, provision for receiving a

perforated record sheet, a motor operated oscillatory type bar actuator, actuating members connected to the type bars and adapted to be selectively engaged by the actuator, and motor operated means rendered effective by selection through the record sheet or by the manual depression of the keys for causing the selective engagement of the actuating members by the actuator, said actuator, having a regular and constant motion.

10. An automatic typewriter having a typewriter keyboard, type bars individual to the different keys but mechanically disconnected therefrom, provision for receiving a perforated record sheet, a power operated type bar actuator, actuating members connected to the type bars and adapted to be selectively engaged by the actuator, oscillatory members rendered effective by the record sheet or by the manual depression of the keys for causing the selective engagement and operation of the actuating members by the actuator, and means for giving said oscillatory members a regular and constant motion.

11. In an automatic typewriter having a keyboard, type bars and provision for receiving a perforated record sheet, a motor operated type bar actuator, actuating members connected to the type bars and adapted to be selectively engaged by the actuator, and two oscillatory motor operated devices one rendered effective by the record sheet and the other by the manual depression of the keys for causing the actuator to selectively engage and operate the actuating members.

12. In an automatic typewriter having a keyboard, type bars individual to the different keys but mechanically disconnected therefrom and provision for receiving a perforated record sheet, actuating levers associated with the different type bars and adapted to shift the same, a motor operated actuator for rocking said levers, and motor operated oscillatory members, one rendered effective by the record sheet and the other by the manual depression of the keys for selectively controlling the engagement between the actuator and the different actuating levers.

13. In an automatic typewriter having a keyboard, type bars individual to the different keys but mechanically disconnected therefrom and provision for receiving a perforated record sheet, actuating levers associated with the different type bars and adapted to shift the same, a motor operated actuator for selectively shifting the different actuating levers to produce the printing operation and two motor operated oscillatory members one rendered effective by the record sheet and the other by the manual depression of the keys for causing the selec-

- tive operation of the actuating levers by the actuator.
14. An automatic typewriter comprising a unitary machine having a keyboard, type bars and provision for receiving a perforated record sheet, actuating members associated with the different type bars and adapted to shift the same, an automatic motor operated actuator for shifting said members; to produce the printing operation, automatic means for causing engagement between the actuator and said members, and means carried by said members for causing operative engagement between said automatic means and the members and adapted to be controlled by the record sheet and manual depression of the keys.
15. In an automatic typewriter having a keyboard, type bars and provision for receiving a perforated record sheet, a motor operated actuator, shiftable members operatively connected to the type bars and adapted to be engaged by the actuator, motor operated means for shifting said members, and spring pressed means released by the record sheet or by the manual depression of the keys for causing said motor operated means to shift the said members so as to be engaged by the actuator.
16. In an automatic typewriter having a keyboard, type bars and provision for receiving a perforated record sheet, a motor driven actuator, actuating members operatively connected with the type bars and adapted to be shifted by the actuator, two motor operated devices for shifting said members into the path of the actuator, and means at opposite ends of said members, those at one end controlled by the record sheet and those at the other end controlled by the manual depression of the keys for causing operative engagement between said members and said motor operated devices.
17. In an automatic typewriter having a keyboard, type bars and provision for receiving a perforated record sheet, a motor driven actuator, levers operatively connected with the type bars and adapted to be shifted by the actuator, two motor operated devices for shifting said levers into the path of the actuator, and spring pressed pins at opposite ends of the levers, those at one end controlled by the record sheet and those at the other end controlled by the manual depression of the keys for causing operative engagement between the levers and said motor operated devices.
18. An automatic typewriter comprising a unitary machine having a frame, a typewriter keyboard at the front of the frame, type bars associated with the different keys of the keyboard, means located at the rear of the frame for receiving a perforated record sheet, actuating members associated with the different type bars, a motor operated actuator, and motor operated means rendered effective either by the record sheet or by the manual depression of the keys for shifting the actuating members to a position such that they may be shifted further by the actuator and thereby swing the type bars to printing position independently of the keys.
19. An automatic typewriter having a typewriter keyboard, type bars associated with the different keys of said keyboard, and provision for receiving a perforated record sheet, actuating members associated with the different type bars, a motor operated actuator, and motor operated means rendered effective either by the record sheet or by the manual depression of a key for positively shifting the corresponding actuating member to a position to be engaged by the actuator so that by further movement of the actuating member independent of the key said actuating member will swing the type bar to printing position.
20. In an automatic typewriter having a keyboard, type bars and provision for receiving a perforated record sheet, actuating members associated with the different type bars, two motor operated members, one rendered effective by the record sheet and the other by the manual depression of the keys for shifting the actuating members to a position such that by further movement they will shift the type bars, and means for imparting such further movement.
21. In an automatic typewriter having a keyboard, type bars, and provision for receiving a perforated record sheet, actuating levers associated with the different type bars, motor operated means rendered effective either by the perforated record sheet or by the manual depression of the keys for giving the levers a predetermined movement, and additional means for then rocking the levers independently of the keys to swing the type bars to printing position.
22. In an automatic typewriter having a keyboard with key levers, type bars and means for accommodating a perforated record sheet, actuating levers connected to the type bars and mechanically disconnected from the keys and levers of the keyboard, a motor operated actuator for rocking the actuating levers to swing the type bars to printing position, and motor operated means rendered effective through selection by the record sheet or by the manual operation of the key levers for shifting the actuating levers into the path of the actuator whereby the automatic operation of the machine takes place without shifting the keys.
23. In a typewriter having a keyboard with keys and key levers, type bars, actuating levers which are connected to the type bars and which are mechanically independent of the key levers, a motor driven actuator.

ator adapted to engage and shift the actuating levers so as to swing the type bars to printing position, and a motor driven member controlled by the manual depression of any of the keys to move the actuating levers to a position to be engaged by the actuator so as to swing the type bars to printing position without further downward movement of the keys.

24. A single unit automatic typewriter which is provided with type bars and provision for automatically operating the same through a record sheet control including levers which are connected to the type bars and a power driven actuator in the path of which the levers are shifted through selection by the record sheet, the typewriter having a keyboard which is unaffected by the automatic operation, and having a motor driven member for shifting said levers into the path of the actuator so that the type bars will be actuated as in the automatic operation.

In testimony whereof, I hereunto affix my
25 signature.
